(57) **CLAIM**

The ornamental design for a control lever for a construction vehicle, as shown.

DESCRIPTION

FIG. 1 is a front perspective view of a control lever for a construction vehicle showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.
